UNITED STATES PATENT OFFICE

143,795

DESIGN FOR A SHOE RACK

Frank P. Case, Chicago, Ill., assignor of one-half to Henry A. Gosling, Chicago, Ill.

Application August 6, 1945, Serial No. 121,249

Term of patent 7 years

(Cl. D33—8)

To all whom it may concern:

Be it known that I, Frank P. Case, a citizen of the United States, residing at Chicago, in the county of Cook and State of Illinois, have invented a new, original, and ornamental Design for a Shoe Rack, of which the following is a specification, reference being had to the accompanying drawing, forming a part thereof.

The figure on the drawing is a front perspective view of a shoe rack showing my new design.

I claim:

The ornamental design for a shoe rack, as shown.

FRANK P. CASE.
